UNITED STATES PATENT OFFICE.

JOHN E. MUHLFELD, OF SCARSDALE, NEW YORK.

LOCOMOTIVE FRAME.

Application filed June 30, 1924. Serial No. 723,093.

This invention relates to locomotive frames and more particularly, to an improved article of manufacture consisting of a one-piece forward or front frame for locomotives in integral form adapted to be rigidly secured to the rear frames of the locomotive and of such construction that the engine cylinders may be separately or independently secured upon and removed from the opposite sides of said front frame.

It is the primary object and purpose of my present improvement to provide such a front frame for locomotives as above characterized whereby, in the event of failure of either of the engine cylinders, it can be easily and quickly detached and removed from said frame without disturbing the connected relationship of the other cylinder with the frame or the connections between said frame and locomotive rear frames and the locomotive smokebox.

In one embodiment of my invention I provide the front frame at its upper end with an integral smokebox saddle structurally independently of the cylinders so that when either of said cylinders is removed from its connection with the frame, the fastening bolts fixing the saddle to the boiler or smokebox wall need not be disturbed. In addition, I provide my new front frame with a forwardly extending integral bumper supporting beam, and a guide for the center pin of the frame of the forward or pony truck of the locomotive.

It is another detail object of the invention to provide simple and effective means for relieving the bolts securing the cylinders to opposite sides of the front frame of shearing strains and to provide means for properly aligning the cylinders with the front frame.

With the above and other objects in view, the invention consists in the improved locomotive frame and in the form, proportion and relative arrangements of its several structural features as will be hereinafter more fully described, illustrated in the accompanying drawings and subsequently incorporated in the subjoined claims.

In the drawings wherein I have illustrated one preferable practical embodiment of the invention and in which similar reference characters designate corresponding parts throughout the several views:

Figure 1 is a side elevation of my im-

proved locomotive front frame, showing the same attached to the forward ends of the rear frame;

Figure 2 is a plan view;

Figure 3 is a fragmentary side elevation of the frame the cylinder being removed; and

Figure 4 is a transverse section taken on the line 4—4 of Figure 1.

In the ordinary locomotive front frame as heretofore used in the art to which the cylinders are bolted and supported, each of the cylinders is formed with one-half of a saddle plate which are bolted together and also bolted to the underside of the boiler wall. Such old and well known construction is illustrated for instance in the U. S. patents to Vauclain, No. 1,076,336 of October 21, 1913, and to Scoville, No. 1,172,841, of February 22nd, 1916. It is obvious that in the event of failure of either cylinder or the steam chest associated therewith, it becomes necessary to remove a large number of bolts connecting the half saddle plates with each other and with the boiler or smokebox as well as the bolts securing the cylinder to the front frame and the bolt connections between the front and side frames or other structural parts of the locomotive before the failed cylinder can be removed and a new cylinder applied and secured in position upon the front frame.

It is the purpose of my present invention to provide means whereby the necessity of removing a large number of bolts will be obviated and which will enable either cylinder to be expeditiously removed by simply removing only the securing bolts whereby said cylinder is fixed to the front frame and without disturbing the bolting between the boiler or smokebox wall and the supporting saddle therefor or between any other parts.

To the above end, as illustrated in the accompanying drawings, in one embodiment of the invention I provide the locomotive front frame in the form of a casting including an intermediate body portion 5 which is of general rectangular form having side walls 6 and end walls 7 connected and reinforced by a number of horizontal webs 8. It will be understood, however, that the specific structural features of this body portion of the frame are not essential and might be variously modified as required in order

to permit of the adaptation and use of my invention in connection with different types of locomotives. However, in every case, the front frame section to which the cylinders 5 are bolted includes forwardly and rearwardly disposed extensions and a bumper beam 9 extending forwardly from the body 5 of the frame, said beam being provided with a vertical guide opening indicated at 10 for the center pin of the pony truck frame and members 11 extending rearwardly from the frame body 5 which may be connected at their ends and at the upper edges thereof by a transverse web 12. In one embodiment of 15 my invention these members 11 are adapted to be positioned against the inner sides of the forward end of the frame 13 of the locomotive structure, the web 12 seating upon flanges 14 on the side frames. The rearwardly extending parts 11 of the front frame casting are rigidly secured to the longitudinal side frames by a large number of bolts 15. Preferably, the frame members are provided with lugs indicated at 16, seating 20 in recesses 17 in the frame 13 whereby the bolts 15 are relieved of shearing strains. Other arrangements of the connection between the front and rear frames may be provided.

Upon the opposite sides of the body portion 5 of the frame, the engine cylinders are mounted. As herein shown preferably, each cylinder 18 and its steam chest 19 is in 30 the form of a one-piece integral casting provided on its inner side with attaching flanges 20, said flanges being preferably recessed as at 21 to receive the lugs 22 on the side walls of the frame body. These lugs afford a convenient means for accurately 35 positioning the cylinder castings upon the sides of the supporting frame and in position whereby the securing bolts indicated at 23, may be inserted through the coinciding openings in the flanges 20 and the walls 40 of the frame body 5. Thus it will be understood that the individual cylinders with the associated steam chest and pipe connections are independently secured and supported by the bolts 23 on opposite sides 45 of the front frames.

In the present instance, I have shown a high pressure cylinder on the right hand side of the front frame and a low pressure cylinder on the left hand side thereof. It 55 will be understood, however, that a high pressure or single expansion cylinder might be substituted for the low pressure cylinder, or any other well known type of locomotive cylinders employed. However, since my improved front frame structure, as herein described and claimed, has been actually used and tested in connection with such a high powered consolidated locomotive constructed for the Delaware & Hudson Company and exhibited to the officers and directors 60 of said company, the week of June 1st, 1924, I have selected the same for purposes of illustration. This locomotive operates under 350 lbs. pressure, and it is therefore evident that an extremely rugged and substantial front frame structure is required.

In the locomotive of this new type, the superheater as well as the direct pressure steam supply pipe connection with the high pressure cylinder and the receiver pipe connection between the high and low pressure cylinders are arranged exteriorly of the boiler or smokebox. In the drawing I have illustrated the superheater steam supply connection with the steam chest 19 of the high pressure cylinder at 24. 25 designates the outlet or exhaust from this steam chest which is connected by a receiver pipe extending over the smokebox with the inlet connection 26 to the steam chest of the low pressure cylinder 18. The exhaust from this cylinder is conducted through the passage 27 formed in the body section 5 of the front frame casting and through a suitable pipe connection to the exhaust nozzle within the smokebox of the locomotive. Thus, it will be understood that a structure integrally connecting two side frame members is provided with a cylindrical steam receiving chamber, and that said frame members extend forwardly and rearwardly from said structure.

One of the important features of my present improvements resides in the provision of a one-piece saddle or seat 28 for the cylindrical boiler shell at the upper end of the body 5 of the one-piece front frame. Preferably, though not necessarily, I design this boiler and smokebox saddle as an integral part of the body structure 5 of the frame, and it will be noted that there is no direct connection of any kind between the cylinders and this boiler and smokebox saddle. Therefore, it will be seen that I have materially simplified prior structures of this character of the types hereinbefore referred to so that it becomes possible to make the separate cylinders of one kind of metal and the locomotive frame and the boiler or smokebox saddle of a different kind of metal. Furthermore, by providing the body structure 5 of the frame as an integral part of the front frame casting, it is possible to provide direct live and exhaust steam connecting passages between the cylinder valve chest and the steam exhaust pipe through said body structure.

However, the most important advantage of the construction above described, resides in the fact that in the event of failure of either of the engine cylinders, it is only necessary to remove the bolting securing said cylinder to the front frame whereby said cylinder with its steam chest can be detached and replaced with a new cylinder

without disturbing in any way the bolting connecting the saddle with the boiler wall, the bolting between the front frame and the rear frames, the bolting between the usual 5 half saddle type of cylinders, the bolting between the half or full saddle type of cylinders and the front frame sections, or other connections. Thus it is seen that the operation of replacing a failed cylinder is 10 greatly expedited and it becomes unnecessary to remove the numerous bolts connecting the same with the boiler or smokebox and independent front frame section which are more or less difficult of access. 15 When the new cylinder has been applied and secured in place by the bolts 23, it is firmly interlocked with the front frame by the lugs 22 seating in the recesses 21, said interlocking connections also operating to 20 relieve the fastening bolts 23 of shearing strains.

I have herein described the novel features of my present invention as used in connection with a two cylinder type of locomotive, 25 but it will be apparent that the essential features thereof might also be incorporated in locomotives having three, four or more cylinders variously arranged and connected with my improved one-piece front frame and saddle construction.

I have herein described and illustrated a practical embodiment of my present invention, which under severe test has been found to be entirely satisfactory. However, it is 35 evident that in the application of my improved front frame to various different types of locomotives, minor mechanical changes may be found necessary. Thus for instance in all cases it may not be found desirable to form the boiler or smoke box saddle 28 as an integral part of the frame casting, and it will be apparent that in such instances this one-piece saddle for the boiler or smoke box may be cast separately and 40 rigidly bolted, keyed and secured upon the upper end of the body section 5 of the front frame. Similarly, as to the several other structural parts of my new locomotive front frame, it will be manifest that the same 45 might be exemplified in numerous other forms, and I accordingly reserve the privilege of adopting all such legitimate changes in the form, construction and relative arrangement of the several detail parts as may 50 be fairly embodied within the spirit and scope of the invention as claimed.

I claim:

1. As a new article of manufacture, a 55 front frame for locomotives consisting of a one-piece integral casting including a body having side and end walls, parallel side frame members extending forwardly from said body, parallel extensions projecting rearwardly from said body for connection 60 with the rear frame of the locomotive, and

a boiler seat saddle integral with the upper ends of said side and end walls of the frame body.

2. As a new article of manufacture, a front frame for locomotives consisting of a 70 one-piece integral casting including a body having side and end walls and horizontally disposed reinforcing webs connecting said side and end walls, said side walls provided with means to receive and support the 75 locomotive cylinders, a boiler seat saddle integrally connecting said body walls with each other at their upper ends, said body having integrally formed rearwardly projecting means for connection with the rear 80 frame of the locomotive and being further integrally formed with forwardly projecting side frame members.

3. As a new article of manufacture, a front frame for locomotives consisting of a 85 one-piece integral structure including a body having side and end walls, parallel side frame members projecting forwardly from said body, and a boiler seat saddle 90 integrally connecting said side and end walls with each other at their upper ends, said side walls of the body adapted to support the locomotive cylinders, and said frame body having a steam passage opening through one of the side and end walls there- 95 of and adapted for direct connection with the steam chest of one of the locomotive cylinders.

4. As a new article of manufacture, a front frame for locomotives consisting of a 100 frame body having side and end walls provided at their upper ends with a boiler receiving saddle, and said frame body having integral forwardly projecting side frames and rearwardly projecting integral parts for 105 connection with the rear frames of the locomotive, the side walls of the frame body adapted to receive and support the locomotive cylinders, and said body having a steam passage opening through one of its side 110 and end walls and adapted for direct connection at one of its ends with the steam chest of one of the locomotive cylinders.

5. As a new article of manufacture, a front frame for locomotives consisting of a 115 one-piece integral casting including a frame body having a one-piece saddle plate at its upper end to receive a locomotive boiler, parallel side frames extending forwardly from said body, spaced parallel parts extending rearwardly from said body and integrally connected with each other at their rear ends, and said body provided with means on the opposite sides thereof for detachably supporting the locomotive cylinders. 120

6. As a new article of manufacture, a front frame for locomotives consisting of a one-piece integral casting including a rectangular body having side and end walls 130

flanged at their upper ends to provide a one-piece boiler receiving saddle, integral side frame members extending forwardly from said body, parts integrally formed with said body and projecting rearwardly therefrom for connection to the rear frames of the locomotive, and said body having a steam passage opening through one of its side and end walls and adapted for direct connection 10 at one of its ends with the steam chest of a locomotive cylinder supported by said frame body.

7. As an improved article of manufacture, a front frame for locomotives consisting of 15 a single integral member having a body provided with forwardly extending side frames and rearwardly extending parallel parts for connection to the forward end of the rear frame of the locomotive, and said body provided at its upper end with an integral one-piece saddle plate adapted to be secured to the wall of a locomotive boiler.

8. As an improved article of manufacture, a front frame for locomotives consisting of 25 a single one-piece member having a body portion upon the opposite sides of which the engine cylinders are adapted to be detachably mounted, said frame body being provided with rearwardly extending parts for 30 connection to the forward end of the locomotive rear frame and with a forwardly projecting bumper beam and having at the upper end thereof a one-piece integral saddle plate adapted to be bolted to the boiler of a 35 locomotive.

9. In a locomotive engine of the cylinder type, the combination of a steam receiving member, and integral side frame members, extending forwardly and rearwardly therefrom on opposite sides thereof.

40 10. In a locomotive engine of the cylinder type, the combination of a steam receiving

member, an integral boiler seat saddle extending vertically above said member, integral side frame members extending forwardly and rearwardly from said steam receiving member on opposite sides of said steam receiving passage.

45 11. In a locomotive engine of the cylinder type, the combination of a steam receiving member, integral side frame members extending forwardly and rearwardly therefrom, on opposite sides thereof, and independent main frame members, rigidly secured to the rear end portions of the side 50 frame members.

55 12. In a locomotive engine of the cylinder type, the combination of a steam receiving member, an integral boiler seat saddle extending vertically above said member and 60 adapted to support a boiler, integral side frame members extending forwardly and rearwardly from said steam receiving member, on opposite sides thereof, and side cylinders secured to said steam receiving member. 65

70 13. In a locomotive engine of the cylinder type, an integral connecting structure, comprising a steam receiving member, side frame members, extending forwardly and rearwardly therefrom, on opposite sides thereof, and a boiler seat saddle extending vertically above the steam receiving member.

75 14. In a steam locomotive, a one-piece body structure having a steam receiving chamber and integral side frame members 80 extending forwardly and rearwardly from said structure on opposite sides thereof and adapted to be rigidly secured at their rear ends to the main frame members of the locomotive.

In testimony that I claim the foregoing as my invention, I have signed my name hereto.

JOHN E. MUHLFELD.
